UNITED STATES PATENT OFFICE.

HERBERT OWEN RUSSELL AND CHARLES LEIGH PAULUS, OF DAYTON, OHIO.

CONDENSER.

Application filed April 18, 1922. Serial No. 555,400.

To all whom it may concern:

Be it known that we, HERBERT O. RUSSELL and CHARLES LEIGH PAULUS, citizens of the United States, residing at Dayton, in the county of Montgomery and State of Ohio, have invented certain new and useful Improvements in Condensers, of which the following is a specification.

This invention relates to electrical condensers in general and more particularly to an improved method of producing same.

The conventional type of electrical condenser is constructed by blanking mica units and blanking lead foil or tin foil units. Lead foil and tin foil are not only difficult to be blanked clean but are very hard to assemble into a condenser, in that they occupy excessive space by reason of the fact that it is practically impossible to assemble this foil without the presence of wrinkles therein. An imperfection in any one of the foil blanks would cause the conducting blank to contact with its opposite and thus destroy the working effect of the condenser.

It is therefore proposed to provide a condenser which will obviate the aforementioned and other difficulties encountered in the use of the conventional type. In accomplishing this result mica separators are blanked out with a punch press and upon one side of each blank a coating of black oxide of lead, graphite, or similar substance is deposited in the form which is ordinarily taken by lead or tin foil separating the mica blanks in the conventional type of condenser. The blanking is then subjected to any suitable electroplating process and a heavy deposit of metal plated over the blanking coated with black oxide of lead or graphite.

This produces a heavy metal deposit on one side of the blank. Projecting from one side of each mica blank is a tab with a row of perforations therein. When the plating process is completed, the tab is broken along the row of perforations, leaving only the projecting tab of metal. The black oxide of lead or graphite is then cleaned off of the projecting tab. For purposes of assembly, holes are punched through the mica, and the condenser units are then ready for assembling.

By placing these units one upon the other, and alternating the sides from which the tabs project, the condenser unit is completed in the preferred form. The tabs on either side are turned down, thus making alternate

connections down each side of the series of tabs. There is provided a brass strip to which the tabs are connected. By this construction there is provided a condenser, in the assembling of which there is eliminated the possibility of the presence of any imperfect blank.

With the foregoing and other objects in view which shall appear as the description proceeds, the invention resides in the combination of parts and in the details of construction hereinafter described and claimed, it being understood that changes therein may be made without departing from the spirit of the invention, the specific embodiment of which is illustrated in the accompanying drawings, in which:

Figure 1 is a front perspective view of the condenser showing the blanks in process of assembly.

Figure 2 is a front perspective view of the condenser showing the blanks fully assembled with the tabs extended.

Figure 3 is a rear perspective view of the same as in Figure 2.

Figure 4 is a view in perspective of the assembled condenser with the tabs bent flush with the ends of the blanks and the contact plates disconnected therefrom, but adjacent thereto.

Figure 5 is a view in perspective of the fully assembled device including the contact plates.

Figure 6 is a wiring diagram of the condenser, showing the electrical connection made by bending the copper tabs over, bringing half of the tabs in contact on one side and the alternates in contact on the other side.

Referring more particularly to the drawings the separators are made of mica and blanked out in the form of blanks A. Each blank A is provided with an extension or tab B. A series of perforations C are made along the edge of the mica blank A for the purpose of enabling the mica tab B to be broken off evenly at the desired time during the process of assembling the condenser.

Upon one side of each of the blanks A a coating of black oxide of lead, graphite, or other similar suitable substance is deposited at D. The space occupied by this substance or coating D is in the conventional type of condenser taken up by tin or lead foil. The mica blank A having the coating D upon one of its surfaces is then put into an electro-

plating apparatus and a heavy deposit of metal plated over the pattern. The graphite or other similar coating is so placed on the mica blank A that there is a clearance between the outer edge of the coating D and the outer edge of the mica blank A, and also a clearance at E around the rivet holes H adapted to receive the rivets I for holding the series of blanks together. Only the 10 coated surface will receive the metal deposit as mica is not subject to an electroplating operation. This clearance is necessary in order to prevent the plated surface from coming into contact with the rivets which bind the entire unit together. The extension or tab B is separated from the mica blank A along the series of perforations C, leaving a thin tab B' of metal, such as copper, electrically deposited on the coated surface of the mica tab or extension. The mica extension is then broken off along the line of the afore described perforations C, and the graphite or similar coating is thoroughly cleaned off of the remaining metal tab by 20 mechanical or chemical means. By placing the blanks one upon the other alternately as shown in Figure 1, a complete unit is formed as shown in Figures 2 and 3, each blank having a metal tab on the side opposite to the tab on the adjacent blank. This assembly is easily accomplished by first providing a suitable fixture having four pins to engage the corresponding rivet holes H in the blank A. The blanks may then be assembled 30 until the proper number is obtained. Referring to Figure 4, contact plates F, provided with lugs G, are slid over the edges of the condenser, crushing the metal tabs into a solid mass and aligning the rivet holes in the blanks. Rivets I are driven through 40 these holes H and riveted over, making a complete condenser unit, as shown in Figure 5.

The entire unit is placed in a dry oven and allowed to remain there until it is thoroughly dry. This is necessary and essential because of the fact that although the pores of mica are small, a remaining small portion of the electroplating fluid would destroy the 50 functioning of the condenser. The contact lugs G are used not only for contact but also to mount the condenser in an instrument such as a magneto. This provides a substantial mounting which is an essential point when the condenser is to be used in connection with magnetos in tractors, airplanes, or similar mechanisms where vibration is of such serious magnitude as to practically prevent the use of a storage battery.

It will thus be readily seen that there is provided a condenser which will be more rugged in construction by reason of its use of copper foil rather than lead foil. The present device will be more cheaply manufactured by reason of the fact that by this

method it is possible to build the entire condenser by the use of an automatic machine, which would be impossible if lead foil is used due to the extreme softness thereof and also the fact that it must be handled after 70 blanking entirely by hand.

In the conventional type of condenser, lead foil of approximately .003 of an inch in thickness is used. While mica separators themselves are .005 of an inch thick, making 75 a total of .008 of an inch, due to the fact that it is practically impossible to eliminate all minute wrinkles from the lead foil, this figure often rises to a point in excess of .010 of an inch in thickness. In the case of a condenser being constructed by the method described in this invention, it is possible to use a mica separator of .005 of an inch thick and deposit upon its surface a coating of black oxide of lead not more than .0005 of an inch 80 thick and upon this surface a copper plate of approximately .0015 of an inch thick, making a total thickness of the entire section of .007 of an inch thick. This figure would be very uniform in all the strips due 85 to the fact that the metal coating is deposited absolutely flat and that the thickness of the metal deposited can be accurately governed by varying the time allowed in the electroplating machine. 90

Having thus described our invention, we claim:

1. An electrical condenser comprising a series of mica sheets, each of said sheets having a coating of material subject to the action of electrolysis such as lead oxide on one face thereof, an electrically deposited plate of copper on said coating. 100

2. An electrical condenser comprising a series of mica sheets, each of said sheets having a coating of material subject to the action of electrolysis such as lead oxide on one face thereof, an electrically deposited plate of copper on said coating, alternately arranged copper extensions on either side 105 of said series of copper plated sheets.

3. An electrical condenser comprising a series of mica sheets, each of said sheets having a coating of material subject to the action of electrolysis such as lead oxide on one face thereof, an electrically deposited plate of copper on said coating, alternately arranged copper extensions on either side 110 of said series of copper plated sheets, said extensions being adapted to be bent flush 115 with the edge of said series of sheets for the purpose of attaching brass contact plates around said extensions at either side of said condenser, and rivets passing through said sheets and contact plates, for the purpose of 120 connecting same together.

4. An electrical condenser comprising a series of mica sheets, each of said sheets having a coating of material subject to the action 125 of electrolysis such as lead oxide on one

- face thereof, an electrically deposited plate of copper on said coating, alternately arranged copper extensions on either side of said series of copper plated sheets, said extensions being adapted to be bent flush with the edge of said series of sheets for the purpose of attaching brass contact plates around said extensions at either side of said condenser, and rivets passing through said sheets and contact plates, for the purpose of connecting same together, and a non-conducting area of mica between the rivets in said rivet holes and the copper plate on said condenser sheets.
- 15 5. A condenser comprising a series of mica sheets, each of said sheets having a superimposed coating of material subject to the action of electrolysis such as lead oxide on one face thereof, a copper plate on said coating, the opposite face of said mica sheet being adapted to come into contact with the copper plate of the adjacent sheet.
- 20 6. A method of making an electrical condenser, consisting in blanking a series of mica sheets with an extension at one side 25 thereof, said sheets having aligned rivet holes, coating one side of each mica sheet and its extension with material subject to the action of electrolysis such as lead oxide and electrically depositing a copper plate on said coating, removing the mica extension and leaving the copper plate thereon integrally attached to the sheet, alternately arranging the sheets with relation to the copper plating and the extensions on said sheets, riveting 30 brass contact plates around the edges of said sheets in such a manner that the extensions will lie flush with the edges of the sheets, there being a space of mica between the rivets and the copper plates on the said 40 sheets, said contact plates having lugs thereon for the purpose of installation in the devices in which the condenser is to be used.

In testimony whereof we have affixed our signatures.

CHARLES LEIGH PAULUS.
HERBERT OWEN RUSSELL.
